[57] CLAIM

The ornamental design for a water distribution control unit, as shown and described.

DESCRIPTION

FIG. 1 is a side perspective view of a water distribution control unit with hose connectors and seal members showing my new design;

FIG. 2 is a top plan view thereof;

FIG. 3 is a side elevation view thereof;

FIG. 4 is a front elevation view thereof;

FIG. 5 is a rear elevation view thereof;

FIG. 6 is an opposite side elevation view thereof;

FIG. 7 is a bottom plan view thereof; and,

FIG. 8 is a side perspective view with the hose connectors and seal members omitted for clarity of illustration only.
